DESIGN FOR A FUR COAT

Simon Etkin, New York, N. Y.

Application May 29, 1939, Serial No. 85,239

Term of patent 3½ years

To all whom it may concern:

Be it known that I, Simon Etkin, a citizen of the United States, residing in New York city, in the county of New York and State of New York, have invented a new, original, and ornamental Design for a Fur Coat, of which the following is a specification, reference being had to the accompanying drawing, forming part thereof.

Fig. 1 is a front view of a fur coat showing my design, and

Fig. 2 is the rear view thereof.

The characteristic feature of my design resides in the combination on the fur jacket disclosed of the contrastingly colored leather collar and edging on the front opening and pockets as shown.

I claim:

The ornamental design for a fur coat, substantially as shown and described.

SIMON ETKIN.
